PRESSING MACHINE

Russell K. Nash, Brookline, Mass., assignor to
Boston Blacking & Chemical Co., Boston, Mass.,
a corporation of Massachusetts

Application June 25, 1934, Serial No. 732,245

21 Claims.

(Cl. 12—52)

This invention relates to pressing machines and is illustrated herein as embodied in a machine for operating upon pieces of sheet material employed in the manufacture of shoes.

It is common practice in the preparation of shoe upper parts, such as vamps and tongues for example, to cause a piece of fabric material to be attached to the leather part as either a lining or a reinforcement for the leather part. These pieces, before being attached to each other, are first cut to the desired shape, the fabric part being somewhat smaller than the leather part, and are then superimposed in register so that their edges are parallel and equidistant from each other at all points. Prior to this invention difficulty has been experienced in effecting attachment of parts located as described above without disturbing their register. This difficulty may arise from one or more of several sources such, for example, as an intermittent feed movement or the application of the feeding force to only one side of the composite work-piece, the movement of which is resisted at the other side by its frictional engagement with a relatively fixed pressing member.

The general object of the invention is to provide a superior machine for pressing together the component parts of a laminated work-piece without disturbing their desired relative positions. While the present invention is illustrated, and will be described below, with reference to effecting the adhesive attachment of two work-pieces, to one side of at least one of which has been applied an adhesive coating, it is to be understood that the invention is none the less applicable with regard to operating upon a work-piece consisting of only a single thickness of sheet material for the purpose of removing wrinkles in it or otherwise reducing it to a substantially flat condition.

In view of the foregoing, one feature of the invention consists in the provision in a pressing machine, of opposed pressing members mounted for movement so as to impart to a work-piece disposed therebetween a continuous feed movement in a closed path, means for holding substantial portions of the pressing surfaces of said members in contiguous relation to each other, and means for causing the remaining portions of said members progressively to be moved relatively to each other, first into and then out of contiguous relation to each other during one circuit of their feed movement. As a result of the pressing members having surface contact with each other over substantial portions of their area a work-piece disposed between the pressing members, in traversing the path of the feed movement referred to

above, not only moves continuously but also receives pressure uniformly distributed over its entire area for a predetermined length of time while the pressing members are held in contiguous relation to each other. Subsequently, the work-piece is moved out of the field of action of the pressing members during the latter part of one circuit of its feed movement so as to facilitate its removal from the machine by the operator.

Further insurance against disturbing the register of the parts of a laminated work-piece, as treated in the illustrated machine, is afforded by the fact that the above-described feed movement is derived as much from one of the pressing members as from the other, the pressing members being mounted, in accordance with another feature of the invention, so as to rotate about a common axis whereby one is driven by the other by frictional engagement without any relative rotation therebetween.

The locality where the pressing members are not in contiguous relation to each other is utilized as a "station" where work-pieces are presented to and removed from the machine, and results from causing one of the pressing members, here illustrated as a flexible disk, to be bent away from the other member which supports the work opposite to that area where they are held in contact, as previously described.

It is now apparent that the work engaging surfaces of the pressing members converge toward the locality where they are held in contact and hence form a bite into which the work-pieces advance after having been placed on the work supporting pressing member. In view of the possibility of a machine operator having his fingers caught at the aforesaid bite, another object of the invention is to insure against his accidentally placing his hand dangerously near to the bite. To this end, another feature of the invention consists in means extending longitudinally of the bite, which, when hit by the operator's hand, actuates other means for controlling the movement of the pressing members so as to stop them before any harm can be caused to the operator. This means, as herein illustrated, is constituted by a latch which not only stops the movement of the pressing members but also tends to prevent the operator from accidentally touching the flexible pressing member which, in the illustrated machine, is normally heated and which therefore might endanger a careless operator for this reason also. In order to minimize danger of this type, the aforesaid latch is also arranged releasably to hold in its operative position means for

rendering the heating means for the pressing member inoperative, so that upon the slightest displacement of the latter under the influence of the operator the means for rendering the heating means inoperative is released and acts accordingly.

These and other features of the invention will be apparent from the following description when taken in connection with the accompanying drawings and will be pointed out in the appended claims.

In the drawings,

Fig. 1 is a view in side elevation of one embodiment of the invention, parts being broken away and shown in section;

Fig. 2 is a plan view of the machine illustrated in Fig. 1 the cover of which has been removed;

Fig. 3 is an enlarged plan view of safety and control apparatus;

Fig. 4 is a view in elevation of the apparatus illustrated in Fig. 3 as viewed from the rear;

Fig. 5 is a sectional elevation of the pressing instrumentalities, the section being taken along the line V—V of Fig. 2; and

Fig. 6 illustrates in perspective one form of work-piece which the illustrated machine is adapted to press.

The illustrated machine is adapted for applying pressure with or without heat to work-pieces in a flat condition with a view either merely to flatten the work-pieces or to cause adhesive attachment of two or more superimposed parts of a work-piece. The invention is illustrated herein with reference to the application of both heat and pressure to a vamp piece for a shoe upper comprising a leather part L, and a fabric part F commonly called a backing or a doubler on one surface of which is an adhesive substance which, when the leather and fabric parts are pressed together, causes their secure attachment. Pressure is applied to such work-pieces in the illustrated machine by pressing means comprising a work support constituted as herein illustrated by a rotary table or support 10 and opposite thereto a flexible pressing member 12 herein illustrated as a disk or plate, the support or table and pressing member being yieldingly held in parallel, contiguous relation rearwardly of their centers by a plurality of rotating conical rolls 14 so spaced angularly as to hold the pressing member 12 in contact with a substantial portion of the area of the table 10. The pressing member 12 is thus driven at the same velocity as the support 10 by frictional engagement therewith. Thus a work-piece, after being placed upon the work support 10 at the front of the machine, receives a feed movement in a closed circular path which carries it through the above-mentioned area underneath the pressing member 12 and the rolls 14 in succession, the weight of which is sufficient in connection with the speed of the feed movement to insure adequate application of pressure to the work-piece to effect the result to be obtained.

Over the upper surface of the support 10 is a fabric covering 16 which is drawn tightly about the support by a lacing 18. The support 10 is fixed to a vertical shaft 20 rotatably mounted in a bearing 22 carried by struts 24 extending between the front and rear portions of the machine frame 26. The shaft 20 is driven by a worm gear 28 which is rotated by an electric motor 30 through connections comprising a worm 32 in meshing relation with the gear 28, the worm itself being carried by a rotatably mounted shaft

34 the end of which adjacent to the motor carries a pulley 36 belted to the pulley of the motor 30. The speed reduction between the motor 30 and the support 10 may conveniently be such as to cause the table to rotate at about 5 R. P. M., although it is to be understood that it may be desirable to employ other speeds, depending upon the operation for which the machine is used, the number and size of the rolls 14, and whether heat, as well as pressure, is employed.

As indicated in Fig. 2, the illustrated machine comprises six of the rolls 14 which are mounted radially with respect to the axis of rotation of the support 10 and are substantially equally spaced and are sufficiently heavy to hold the pressing member 12 in contiguous relation to substantially one half of the surface of the support 10. The position of the rolls 14 is maintained by inner and outer guards 38 and 40, respectively, which are bolted to a cross piece 42 extending between upright portions of the frame 26 at the front of the machine and at the rear to an upright standard. Each roll 14 is in the form of a truncated cone consisting of solid metal or similar heavy material and has pintles 44 extending from each end. The pintles 44 near the center of the machine are received between the arms of bifurcated guides 46 which are bolted to the inner guard 38, and the outer pintles 44 are received within notches in guides 48 which are bolted to the outer guard 40. By means of collars 50 adjustably fixed on the outer pintles 44 and disposed one at each side of the guides 48, axial movement of the rolls 14 relatively to the center of the machine can be controlled to a certain extent. The rolls 14, while being rotated idly by contact with the pressing member 12 beneath them which is driven by the work support 10, are constrained against axial movement as mentioned above but are allowed to yield upwardly in response to the tendency of work-pieces to lift the pressing member 12 while it passes through the locality where it is acted upon by the rolls 14.

To facilitate the placement on and removal from the work support of the work-pieces, the pressing member 12, which is illustrated herein as a flexible metallic disk, is bent upwardly at the front portion of the machine and is thus held by a post 52 on which is mounted a ball bearing 54 so that the outer element of the ball bearing engages the lower side of the pressing member 12 adjacent to the edge. Axial alignment of the pressing member 12 with the support 10 is insured by a dowel 56 mounted at the axis of the work support 10 and received in a perforation in the center of the pressing member 12. In case of its being desirable to apply not only pressure but also heat to a work-piece either for flattening it or for causing its components parts to be adhesively united, the illustrated machine includes means for heating the pressing member 12. This means, as illustrated, comprises a gas burner 58 having perforations in its lowermost part so as to direct the flame toward the upper surface of the pressing member 12 directly beneath the burner. Thus, as successive sectors of the pressing member 12 pass beneath the burner when the pressing member is rotated, it is heated to a temperature sufficient to facilitate a simple pressing operation in one case, or to render tacky a heat-responsive adhesive with which the surface of a backing or doubler part adjacent to a leather part is coated. The burner is supported by brackets 60, 60 which are secured to the guards 75

38 and 40, so as to extend substantially radially of the pressing member nearly to its center, as illustrated in Fig. 2. Gas is supplied to the burner 58 through a pipe 62 and the flow of gas is interrupted or regulated by a valve 64 which is operated in conjunction with a switch 66 for starting and stopping the motor 30, and a brake 68 for stopping the rotation of the work support 10, as will be described below.

10 The valve 64 is operated so as to control the flow of gas through the pipe 62 by a controller herein illustrated as a lever 70 which normally, when the machine is in operation, occupies the position in which it is illustrated in Figs. 3 and 4, 15 in which operative position it also causes the switch 66, a well-known type of toggle switch, to close a circuit which delivers electrical power to the motor 30. The lever 70 is normally urged in a clockwise direction (Fig. 4) by a link 72 which is connected to one arm of a bell crank 74, to the other arm of which is connected another link 76. The link 76 at its rearmost end is connected to one arm of a bell crank 78 pivotally mounted on the strut 24, the other arm of which bell crank carries the brake 68 in such a position as to engage the rim of the pulley 36 when swung toward it. A spring 80 connected at one end to the frame and at the other to the depending arm of the bell crank 78 yieldingly 20 holds the brake 68 against the pulley 36 when the lever 70 referred to above is released, as will be described below.

The lever 70 is held in its operative position, in which it is illustrated in Fig. 4, against the tension of the spring 80, by means of a latch member 82 having a pin 84 adapted to be received within a perforation in the upper end of the lever 70. The latch member 82 is mounted at its left-hand end (Figs. 2 and 3) on a pin 86 fixed thereto and slidably received in a bracket 88 fixed to one of the upright members of the frame 26. A compression spring 90 surrounding the pin 86 and bearing against the bracket 88 is arranged normally to hold the latch member 82 against the adjacent side of the lever 70 so as to cause the pin 84 to releasably hold the lever 70 in its operative position. The latch member 82 is mounted at its right-hand end (Fig. 2) on a hinge 92 so as to allow the latch member to swing to a certain extent, limited by the pin 86, when touched by the operator. It will be noted by reference to Fig. 5 that the latch member 82 is positioned well toward the bite formed where the work engaging surfaces of the pressing member and support 10 converge and hence serves to prevent the operator from burning his fingers by touching the pressing member 12 as might easily result from placing them too far toward the center of the machine in presenting a work piece thereto. The latch member 82 also insures that the machine will be stopped if the operator should accidentally place his hand dangerously near the bite between the pressing member and the work support, as will now be described. The strength of the spring 90 is so slight as to allow the latch member 82 to be moved inwardly toward the center of the machine, thereby to release the lever 70 upon a very slight amount of pressure being exerted against it, as might occur if the operator's hand were accidentally moved against the latch member 82 or underneath it. Such movement of the latch member 82 causes the pin 84 to be moved away from the lever 70 which then, under the influence of the spring 80, swings rapidly in a clockwise direction (Fig. 4) to its

inoperative position and causes the switch 66 to open the electric circuit to the motor, thereby stopping the latter, closes the valve 64 turning off the heat, and also causes the brake 68 to be applied to the pulley 36 for the purpose of stopping the rotation of the work support 10. For convenience in starting the machine again there is provided a hand lever 94 which can be swung from its dotted line position in Fig. 3 to the full line position to reset the latch 82 and to start the operation of the machine both by turning on the gas and causing rotation of the work support 10. A pilot burner (not shown) may be associated with the burner 58 to ignite the gas when the gas valve 64 is turned on. For the purpose of conserving heat and maintaining the temperature of the pressing member 12 as nearly constant as possible, the uppermost portion of the machine is covered by a casing 96 arranged to fit snugly over the outer guard member 40 and to extend downwardly as far as the level of the work support 10, as illustrated in Fig. 1. For the convenience of the operator in presenting work pieces to the machine and in caring for the finished work, the machine is equipped with a table 98 fixed to the frame of the machine at the front directly beneath the work support 10. In the operation of the machine for effecting the attachment of superimposed parts of a work-piece of the type illustrated in Fig. 6, the machine is first started by operating the lever 94 so as to start the motor 30 and to open the valve 64. The machine is then run idly until the pressing member 12, as a result of rotating beneath the burner 58, has been brought to the desired temperature. At this point the operator may begin placing the shoe parts to be united in register with each other on the work support 10, as indicated for example in Fig. 2, the rotation of the work table being so slow as not to disturb the register of the parts of the work-piece as they are placed on it. The work-piece is thus placed on the work support 10 at any desired locality where the pressing member 12 is bent upwardly away from it. This position may conveniently be toward the left-hand side of the machine (Fig. 2) so as to allow the operator space and also time for the removal of work-pieces from the machine as they emerge from the bite between the support 10 and pressing member 12 at the right-hand side of the machine. Owing to the rotary movement of the work support 10, it imparts to a work-piece placed thereon a continuous feed movement in a closed circular path. The pressing member 12 also participates in feeding the work by being driven at the same speed as that of the work support 10 by frictional engagement with it at points not covered by the work-piece. For this reason the advance of the work-pieces through the machine results as much from the force applied to its upper surface by the pressing member 12 as from the force applied by the work support 10 to its lower surface whereby the possibility of the parts of a laminated work-piece being misaligned during the pressing operation is minimized. A substantially uniform application of pressure to the work-pieces is thus effected as a result of the parallel, contiguous relation of the pressing member and the work support which is insured by the rolls 14 which yieldingly hold the pressing member 12 and work support 10 together while passing through substantially a half revolution. As a work-piece passes beyond this locality, successive portions of the pressing member 12 are bent first upwardly away from the work support, fa-

cilitating the removal of the work-piece from the support at the front of the machine, and then downwardly again toward the work support 10.

- In the normal operation of the machine, the lever 70 is held in its operative position, as is described above, by the pin 84 which extends into the perforation in the upper end of the lever thereby resisting the tendency of the spring 80 to cause the lever 70 to be swung to its inoperative position. If, however, the operator carelessly places his hand or hands so near to the bite between the pressing member 12 and the table 10 as to endanger them by burning or by being seized in the bite, the latch member 82 is swung inwardly against the resistance of the spring 90 in response to the lightest pressure from the operator's hand so as to withdraw the pin 84 from the lever 70. Thereupon the lever 70 swings rapidly from its full line position, as illustrated in Fig. 3, to its dotted line position and carries the hand lever 94 also to its dotted line position from which it can be moved by the operator to start the machine again.

Having thus described my invention, what I claim as new and desire to secure by Letters Patent of the United States is:

1. In a pressing machine, opposed pressing members, said pressing members being mounted for movement so as to impart to a work-piece disposed therebetween a continuous feed movement in a closed path, means for holding substantial portions of said members against movement relatively to each other and in contiguous relation to each other during a portion of one circuit of their feed movement, and means for causing the remaining portions of said members progressively to be moved first out of and then into contiguous relation.
2. In a pressing machine, opposed pressing members, said pressing members being mounted for movement so as to impart to a work-piece disposed therebetween a continuous feed movement in a closed path and having pressing surfaces which are continuous in the direction of the said feed movement, and means for causing opposite successive portions of said members to be moved progressively away from and then toward each other during their passage between spaced localities in said path, and also to be held in contiguous relation to each other during their passage of the remainder of the said path.

3. In a pressing machine, opposed pressing members, means for rotating said pressing members in order to impart to a work-piece disposed therebetween a circular feed movement, means for deflecting successive portions of one of said members progressively away from the other of said members during their passage of a predetermined sector of their feed movement to facilitate the placement of a work-piece therebetween, said means also being constructed and arranged to hold said members in contiguous relation to each other during their passage of the remainder of one circuit of their feed movement.

4. In a pressing machine, opposed pressing members comprising a rotary table and disk, means for rotating said table to impart to a work-piece disposed thereon a feed movement in a circular path, means for holding the pressing surface of said table and disk together against relative movement while traversing a sector of said path, and means for holding the pressing surfaces of said table and disk apart while they are traversing the remaining portion of said path.

5. In a pressing machine, pressing means comprising a support and a flexible pressing member, means for moving said support to impart to a work-piece disposed thereon a feed movement in a closed path, means acting upon one side of said pressing member to cause its pressing surface to be held in contiguous relation to the support throughout a portion of said path, and means acting upon the other side of said pressing member for holding its pressing surface away from the support throughout the remainder of said path.

6. In a pressing machine, opposed pressing members mounted to rotate about a common axis and having pressing surfaces which are continuous in the direction of their rotation, and means for causing opposite successive sectors of said pressing members to be moved relatively to each other alternately into and out of parallel contiguous relation to each other.

7. In a pressing machine, opposed pressing members mounted for movement about an axis so as to impart a feed movement to a work-piece disposed therebetween in a plane perpendicular to said axis, rolls acting upon one of said pressing members to hold their pressing surfaces in contiguous relation to each other throughout a portion of said feed movement, and means for causing said pressing surfaces to be separated from each other elsewhere throughout said feed movement.

8. In a pressing machine, pressing means comprising a rotary table and a flexible disk, means for moving said table to impart a circular feed movement to a work-piece thereon, means for holding a sector of said disk against said table, and means for causing the remaining portion of said disk to be deflected away from said table.

9. In a pressing machine, rotary pressing members mounted for movement about a common axis one of which members is rotated by frictional engagement with the other thereby to impart to a work-piece disposed therebetween a feed movement in a closed path, means for holding the pressing surfaces of said members together while they turn through a portion of said path, and means for holding the said pressing surfaces apart while they are traversing the remaining portion of said path.

10. In a pressing machine, rotary pressing means comprising a support and a pressing member mounted to rotate about a common axis, the cooperating surfaces of said support and pressing member being continuous in the direction of their movement, rolls mounted and arranged to hold the support and pressing member in contiguous relation to each other as they pass through a predetermined sector of a revolution, and means for relatively separating said support and pressing member as they are moved through the remainder of said revolution.

11. In a pressing machine, a rotary support, a flexible pressing member, means for holding said pressing member in pressing relation with the support as they turn through a predetermined sector of one revolution whereby said pressing member is rotated by frictional engagement with the support, and means for bending said flexible pressing member away from the support as they turn through the remaining portion of one revolution thereby to facilitate the insertion of a work-piece between said pressing member and support.

12. In a pressing machine, a rotating support, a pressing member constructed and arranged to be separated from the support at a locality where

work to be pressed is presented to said support, and means for yieldingly holding said pressing member against said support opposite the above-mentioned locality thereby to cause the latter to be rotated by frictional engagement with and at the velocity of the support.

13. In a pressing machine, a rotatable work support, a pressing member cooperating with said support to exert pressure upon a work-piece disposed therebetween, means for rotating said support to impart to the work-piece a feed movement in a circular path, said support and pressing member being mounted so that their pressing surfaces are in contiguous relation to each other throughout a substantial portion of said path whereby said pressing member is rotated by frictional engagement with said support, and means for separating said support and pressing member as they are moved through the remainder 20 of said path to facilitate the placement of a work-piece therebetween.

14. In a pressing machine, a rotary work supporting table, a flexible pressing member mounted to rotate about the axis of rotation of said table, means for yieldingly holding said pressing member in contact with a substantial portion of the area of said table, means for rotating said table and said pressing member, and means disposed between said table and pressing member opposite said area mounted and arranged to deflect said pressing member away from said table to facilitate the placement of a work-piece therebetween.

15. In a pressing machine, a rotary support, a flexible pressing member, rolls for yieldingly holding said pressing member in contact with a substantial portion of the surface of said support, means for rotating said support whereby said pressing member is rotated by engagement there- 40 with, and a member spaced from said work support adapted to engage the side of said pressing member adjacent to said work support for causing said pressing member to be bent away from said support opposite to said area where they 45 are held in contact with each other.

16. A machine of the class described having, in combination, rotary feed members having converging surfaces to form a bite, driving mechanism for rotating said members, and means for normally maintaining said mechanism operative and for rendering said mechanism inoperative if the operator's fingers approach too near the bite of the rotary members, said means comprising a controller the position of which determines the 55 operativeness or inoperativeness of the driving mechanism, means tending at all times to urge

the controller to move into position to render the driving means inoperative and a latch located in front of the bite of the rolls and acting to hold the controller normally in position to render the driving mechanism operative.

5

17. In a pressing machine, rotary pressing members the work-engaging surfaces of which converge to form a bite, means for heating one of said pressing members, means for rendering said heating means inoperative, and operator controlled means disposed at said bite between the pressing members for actuating said last mentioned means.

18. In a pressing machine, rotary pressing members the work-engaging surfaces of which converge to form a bite, means for heating one of said pressing members, means for controlling said heating means tending normally to render it inoperative, and means for actuating said controlling means to render said heating means inoperative disposed between said pressing members at the said bite.

19. In a pressing machine, pressing members the work-engaging surfaces of which converge to form a bite, means normally operable to move said members to impart a feed movement to a work-piece disposed therebetween, means for controlling said last mentioned means arranged to tend to render it inoperative, and an operator controlled latch disposed at said bite arranged normally to prevent said controlling means from stopping the feed movement of said pressing members.

20. In a pressing machine, pressing members the work-engaging surfaces of which converge to form a bite, means for heating one of said presser members, means for controlling said heating means constructed and arranged to tend to render it inoperative, and an operator-controlled latch disposed at said bite mounted and arranged 40 releasably to hold said controlling means in its operative position.

21. In a pressing machine, rotary pressing members, means for moving said pressing members to cause a feed movement to be imparted to a work-piece disposed therebetween, means for heating one of said pressing members, means arranged normally to render said heating means inoperative, means for controlling said heating means and the said first mentioned means constructed and arranged to tend normally to render them inoperative, and an operator-controlled latch disposed at the said bite between the said pressing members for releasably holding said controlling means in its operative position.
